Edgar T. Meakin, San Francisco, Calif.

Application October 14, 1940, Serial No. 361,045

5 Claims. (CL 100—43)

My invention relates to presses, and more particularly to control means for presses of the screw type.

In presses adapted, for example, to the extrusion of juice or oil from fruits, seeds, fish or the like, as the case may be, most satisfactory and efficient operation, and consequently, a resulting greater recovery, is realized within the region of a certain operating pressure within the extrusion chamber. What this pressure will be is determined in large measure by the kind and type of material to be operated on. Any factor which tends to load or lighten the load on the press will result in a departure from the best operating conditions within the extrusion chamber, even to the extent at times of causing jamming of the press. The pressure within the extrusion chamber must, as a consequence, shift outside of the relatively narrow range of efficient operating pressures, to a value representing a lower recovery and, consequently, poorer efficiency. It is, therefore, desirable to maintain a substantially constant pressure within the extrusion chamber, in spite of any factors tending to upset this condition.

Prior attempts to solve this problem have not been entirely satisfactory, such attempts, for the most part, taking the form of manually controllable cone operating means for the solids discharge passage from the extrusion chamber. An operator, finding the machine not operating properly, makes whatever manual adjustment he desires or thinks necessary to remedy the situation, often discovering the condition too late to preclude upsetting the operating pressure or jamming of the press.

Among the objects of my invention are to provide a newly designed extrusion press.

(1) In which the operating pressure shall be maintained within relatively narrow limits, in spite of any factors tending to shift such pressure beyond these limits.

(2) In which any tendency for jamming to occur will bring about a rapid and complete release of the contents of the extrusion chamber, as a step toward restoring the machine to normal operation.

(3) In which the operating pressure will be maintained through hydraulic means.

(4) In which the proper operating conditions shall be maintained automatically.

(5) In which pressure maintaining means is provided that is adjustable to maintain different values of operating pressures, and

(6) In which the pressure regulating means

is made automatically responsive to the load variations which the press during operation places upon its driving motor.

Additional objects of my invention will be brought out in the following description of the same taken in conjunction with the accompanying drawings wherein—

Figure 1 is a sectional view in a vertical plane through a continuous type press with a preferred embodiment of my improved control system incorporated therein.

Figure 2 is a plan view, enlarged, of that portion of the control means which forms part of the press structure of Figure 1, and

Figure 3 is a view in section of the structure of Figure 2 taken on the line 3—3 of said figure.

In a general way, my invention contemplates provision of automatic means directly or indirectly responsive to the pressure within the extrusion chamber, for adjusting various factors to maintain such pressure within a narrow operating range conducive to efficient operation and maximum recovery. To this end, in my preferred embodiment, I provide a hydraulic control system which normally tends to urge the cone to closing position in the discharge passage from the extrusion chamber, but which is rendered responsive to an overload on the press driving motor, for quickly retracting the cone to its extreme open position.

If such overload value be selected which is indicative of a condition in the press extrusion chamber, conducive to jamming of the press, then maximum opening of the solids passage of the press will occur only under such extreme condition of operation, to preclude the development of dangerous pressures within the extrusion chamber and permit elimination from such chamber of the solid products tending to clog the same.

For conditions of less seriousness, developing in the press, which may have a tendency to fluctuate the pressure condition therein, the hydraulic system is provided with a relief valve which will operate to maintain a normal pressure condition, by permitting the cone to vary the discharge opening in accordance with such factors tending to alter the operating pressure.

For a more detailed description of my invention, reference will be made to the accompanying drawings wherein I have disclosed my invention as applied to a continuous screw type press for the extrusion of juices or oils from various products.

This type of press, in general, comprises an extrusion chamber having at one end an in-

tegrally formed hopper 3 for the introduction of the products to be pressed, while at the other end, the extrusion chamber is open for the discharge of the solid products remaining after the recovery of the juices or oils therefrom. The juices or oils are extruded through an intermediate portion of the extrusion chamber which is formed of heavy screening 5 reinforced by longitudinal ribs 6 and transverse ribs 7. At its open end, the extrusion chamber is supported upon a standard 8.

The hopper end of the extrusion chamber enters a wall 9 of a gear housing 11, and is affixed thereto by suitable bolts or the like. The gear housing, in turn, is supported on a standard or base 13, whereby the hopper end of the extrusion chamber will be maintained at a common level with the open end of the extrusion chamber.

The extrusion member in the continuous type of press, constitutes a screw 15 extending axially of the extrusion chamber. This screw comprises a tapered shaft 17 terminating in a large hollow end 19 at the discharge end of the extrusion chamber, and of a diameter somewhat smaller than the open end of the extrusion chamber, the space 21 thereby provided between this end of the screw shaft and the extrusion chamber constituting the discharge opening for the solid products of the press. The tapered shaft 17 carries a spiral rib or thread 23 from the hopper end of the screw shaft to an intermediate point along the screen 5, short of the discharge end of the extrusion chamber. This rib is of a height causing the same to practically reach the wall surface of the extrusion chamber.

The screw 15 is mounted for rotation, at its driven end, by a shaft extension 25 supported in suitable bearings 27 and 29 at opposite sides of the gear housing. This shaft extension carries a drive gear 31 which is in mesh with a driving pinion 33 fixed to the shaft 35 of a driving motor 37. Lubrication of the gear and pinion assembly is effected by an oil reservoir 39 at the bottom of the gear casing, and into which the gear 31 dips.

At its enlarged hollow end, the screw shaft 17 is provided with a shaft extension 41 passing out through the open end of the extrusion chamber. The end portion of this shaft extension is of reduced cross section. A U-shaped bracket 42 affixed to the open end of the extrusion chamber carries a bearing 43 through which the reduced portion of the shaft extension passes and is journaled.

In the operation of a press of this character, the product to be pressed is placed in the hopper 3 and, due to the screw construction, such material is compressed to an increasingly higher degree, as the product is carried along by the screw 15 toward the discharge end of the extrusion chamber. The juice or oil thus pressed from the product passes through the screen 5 of the extrusion chamber and is caught in a tank 45 positioned below the extrusion chamber for the purpose. A suitable guard casing 46 may be placed around the extrusion chamber as a protection.

It has been found that maximum recovery, and accordingly higher efficiency of operation, may be expected in a press of this character, when operating within a very narrow range of pressures, the particular range depending upon the type and quality of the product to be operated on. Many factors, however, tend to disturb such

operating condition within the extrusion chamber, and as an example of this, it might be pointed out that any variation in moisture content, or physical characteristic, or degree of ripeness in the product to be pressed, may tend to vary the load on the press and upset the desired pressure conditions therein. Such disturbing factors can be compensated for and eliminated in accordance with my invention, by varying the effective size of the discharge passage to relieve any tendency for such a variation in pressure condition within the extrusion chamber to develop; and under extreme conditions, where jamming tends to occur, the solids or discharge passage will be opened to its maximum extent to permit discharge of the accumulations which have built up within the extrusion chamber.

To this end, on the shaft extension 41, I slidably mount a hollow cone 47 with its small end open and adapted to slide over the hollow end 19 of the screw shaft. The cone is provided with an inwardly directed collar 49 which is preferably, though not necessarily, keyed to the shaft extension, to preclude relative rotation of the cone with respect to the shaft, without impairing its ability to slide along such shaft extension. The base 51 of the cone is formed with a plurality of integral bosses 53 distributed concentrically of the shaft extension 41 for the purpose of anchoring therein a number of bolts 55 extending parallel to the shaft extension.

The shaft extension 41 is provided with a fixed piston 57, to each side of which there is affixed a cupped leather washer 59 in which is placed a filler ring 61. These filler rings are held in place and at the same time serve to hold the cupped leather washers 59 in position against the piston, by means of a plurality of rivets or bolts 63, the heads of which are permitted to protrude from the filler rings.

The piston 57 is surrounded or enclosed by a movable cylinder 64 which is affixed to the base 51 of the cone. This cylinder includes a plate 65 mounted on the bolts 55 and shaft extension 41, in abutment against the cone bosses 53, and a flanged collar 67 slidably mounted about the shaft extension and having a flange 69 at one end and smaller flange 71 at the other end. The flange 69 is threaded to the collar and is provided with a number of bolt openings adjacent its periphery, for receiving the ends of the bolts 55. The plate 65 and the flange 69 are each provided with a circular groove to receive a cylinder wall 73 which is clamped therebetween by the application of clamping nuts 75 to the ends of the bolts. The internal end surfaces of the cylinder thus formed, are each provided with a cupped leather washer 76 and a filler ring 77 similar to those applied to the fixed piston 57. The holding rivets or bolts 78 for these washers 76 and rings 77, are positioned in alignment with the corresponding elements 63 on the piston, so that when either end of the cylinder abuts against the piston, a residual chamber or space will remain.

The cone and the cylinder, by reason of the construction just outlined, are accordingly capable of movement along the shaft extension, as a unit. The extent of such movement is controlled by a movement limiting collar 79 which is threaded to a cylindrical mounting 81 on the shaft extension 41, in spaced relationship to the shaft extension, and has an inturned flange 83 adapted to function as a limiting abutment in the movement of the flanged collar 67.

in either direction. The extent of travel or movement of the cone in the direction of opening of the discharge passage, may be increased by adjustment of this adjusting collar in the desired opening direction, the adjusting collar being provided with suitable handles 84 to facilitate such adjustments. The assembling of this adjusting collar is facilitated by the threaded connection of the flange 69 on the collar 67.

The shaft extension is provided with a pair of longitudinal bores 85 and 87. One of these connects with a lateral bore 88 entering the cylinder to one side of the fixed piston 57, while the other longitudinal bore terminates in a similar lateral bore 89 entering the cylinder at the other side of the piston.

At the end portion of the shaft extension, provision is made for effecting a fluid connection from the outside, to each of these longitudinal bores. This portion of the shaft extension is surrounded by a flanged stationary cap 91 which is bolted to the bearing supporting portion of the U-shaped bracket 42, with a partitioning wall 93 between the bracket and the cap, to create a chamber within the cap.

The cap chamber is divided into two compartments 95 and 97. One of these compartments 95 is connected with one of the longitudinal bores 85 by means of a connecting lateral bore 98, and provides for connection to an external duct or conduit 99 through an opening in the wall of the cap. Similarly, the second compartment 97 provides for connecting the other longitudinal bore 87 with an external conduit 101.

Each of the compartments in the cap is formed by a pair of oppositely disposed cupped leather washers 103 and 105, each with a filler ring 107 and 109, respectively, nesting therein. The oppositely disposed leather washer and filler ring assemblies are maintained in spaced relationship by a spacer ring 111 which is perforated radially to maintain fluid connection between a longitudinal bore 85 or 87 in the shaft extension and its associated conduit 99 or 101, respectively. These associated conduits 99 and 101 leading from the cap compartments, connect with the load side of a flow reversing valve 113. The load side of such valve is considered as that part of the valve which is fluid connected to the load, which in this case is the adjusting cone assembly.

The source of liquid utilized in the hydraulic control of the cone adjustment, preferably constitutes the lubricant reservoir in the gear housing 11, which, under the circumstances, performs the two entirely unrelated functions of (1) serving as the lubricant for the gear and pinion assembly in the gear housing, and (2) constituting the operating fluid in the hydraulic control mechanism. The lubricant enters the hydraulic system at the intake side of a fluid pressure pump 115, preferably one of the gear type. This pump in the system disclosed, is submerged in the lubricant reservoir, and is chain driven from a pulley 117 on the screw shaft extension 25 in the gear housing. A conduit 119 extends from the pressure side of the pump, and makes connection with the pump side of the flow reversing valve 113. A similar conduit 121 connecting with the flow reversing valve, also on the pump side thereof, extends back to the gear housing and terminates therein at a point preferably below the level of the lubricant therein, and serves to return the hydraulic fluid to the reservoir.

The flow reversing valve 113, sometimes

termed a "four way valve," may be of any well known construction or type of which there are many on the market. The one which I have depicted as an element of the system, includes 5 a valve chamber 123 of tubular shape. The two conduits 99 and 101 connect to this chamber at spaced points on one side thereof, while the conduit 119 from the pump 115 enters the chamber from an opposite side thereof and at 10 a point substantially intermediate the connections of the other conduits. The return conduit 121 to the lubricant reservoir enters the valve chamber through the bottom thereof. The valve 113 includes a plunger 125 within the 15 chamber, having an intermediate portion 127 of restricted diameter. The plunger is of such dimensions with respect to the entrances to the chamber from the conduit 119 and the load conduits 99 and 101, that, regardless of its position, the conduit 119 will always discharge around the restricted portion of the plunger, while at alternate positions of the permissible stroke of the plunger, either one or the other of the load conduits 99 and 101 will be exposed to such discharge. The plunger is further provided with a 20 longitudinal bore 129 extending from the bottom of the plunger to intersect a transverse bore 131 in the stem portion 133 of the plunger. The function of this bore is to provide for a liquid 25 passage connection between the load conduit 99 and the return conduit 121, when the plunger is at the extreme end of one of its strokes, in its lowermost position, for example, as indicated in the drawings. In such position, the load conduit 101 associated with the closing operation of 30 the cone, will be in liquid communication with the conduit 119 leading from the pump, and consequently will serve to carry fluid under pressure, to that side of the piston which will cause 35 the cylinder to move the cone in the direction of closing of the discharge passage.

Any fluid in the cylinder on the other side of the piston will necessarily have to be discharged therefrom, to permit such movement of the cylinder, and such fluid will accordingly discharge 45 through the other conduit 99, and through the return conduit 121 via the bore 129 in the plunger, from which conduit, the fluid will be discharged into the lubricant reservoir in the gear 50 housing.

With the plunger in its uppermost position, the direction of flow in the load conduits 99 and 101 will be reversed, and that portion of the cylinder to the right of the piston in Figure 1 55 will receive lubricant under pressure, to effect withdrawal of the cone from its previous position. Under such condition, the liquid on the other side of the piston will discharge through the load conduit 101 and valve chamber 123, directly into the return conduit 121, to the lubricant reservoir.

Under normal conditions of operation, the condition and position of the plunger will be as indicated in Figure 1 of the drawings, wherein 60 the hydraulic pressure will be in a direction tending to bring about movement of the cone to a closing position.

A relief valve assembly 135 interconnects the pump conduit 119 and the return conduit 121. 70 This valve comprises a valve casing 137 partitioned by a valve seat 139 to provide an intake chamber 141 to which the pump conduit 119 connects, and a discharge chamber 143 which connects with the return conduit 121. A valve 145 in the discharge chamber has a valve stem 147

protruding therefrom. A spring 149, under compression, bears against the valve in the direction of seating the same. An adjusting screw 151 permits adjustments in the spring pressure to alter the operating pressure characteristics of the valve assembly.

For all conditions or factors, short of producing jamming in the press, no change in the flow reversing valve is contemplated. Fluctuations or changes in the position of the cone 47, to vary the discharge path opening, are nevertheless provided for, to compensate for such conditions or factors, by the relief valve, the passage through which will vary in accordance with the prevailing pressure differential existing at any instant between the two sides of the hydraulic system. Such pressure differential will vary in response to any movement of the cone, brought about by the development of such factors or conditions which tend to disturb the existing pressure condition within the extrusion chamber. Thus, the pressure on the cone side of the piston will tend to increase in accordance with any tendency toward an increase in the pressure developing in the press. Such tendency toward an increase in pressure is in opposition to the pumping pressure, and consequently will cause opening of the relief valve to an extent sufficient to take care of the overload on the pump and bring about a reduction in the prevailing tendency to increase the pressure on the cone side of the piston. Such pressure relief is attributable directly to a slight reverse or back-flow of hydraulic fluid permitted by the opening of the relief valve. The relief valve is preferably made sufficiently sensitive to such tendencies toward pressure changes, that the pressure on the cone side of the piston, under the conditions noted, will never be permitted to vary beyond the narrow range conducive to efficient operation of the press.

The movement of the cone against such maintained hydraulic pressure, in the direction indicated, serves to relieve the increasing pressure condition developing within the press, while precluding any substantial variation in the pressure within the extrusion chamber. Following elimination of the cause, the pressure within the press will tend to drop, whereupon the cone will then move in the direction of its former position, under the hydraulic pressure developed by the pump to maintain the pressure at the desired operating value, the relief valve in the meantime also being restored to its normal position.

As previously indicated, it is desired that the flow reversing valve 113 operate preferably only under such conditions as are apt to cause jamming of the press, and such reversal can be governed or controlled by the load placed upon the driving motor 37 under such conditions. Accordingly, the valve is provided with a solenoid 153 about the plunger stem 133, and this solenoid is connected across two of the lines supplying the motor. If the motor is a three phase motor, as is indicated in the drawings, then the solenoid will be connected across any one of the phases. This solenoid circuit normally includes the open contacts 155 of a relay 157 in one of the lines to the motor. The relay is designed or adjusted to become energized when the current drawn by the motor 37 reaches an overload condition indicative of possible jamming of the press, and when such overload condition is reached, the relay will close its normally open contacts 155 and energize the solenoid 153,

whereupon the plunger 125 will be moved to its other extreme position, and bring about a reversal of flow of the liquid in the load conduits 99 and 101. Such reversal of flow will shift the pressure from the cone side of the piston 51, which normally tends to move the cone to closing position, to the other side of the piston, which shift of pressure will operate to slide the cone to its maximum permissible open position. With the cone in its maximum permissible open position, the greatest relief is offered to the press, and such maximum open position will be maintained so long as the relay 153 is energized, and this will be determined by the continued existence of such conditions within the press, tending to produce jamming. As soon as the press becomes relieved of such condition, as by the discharge of any accumulated solid products from the extrusion chamber, the load on the driving motor will diminish to normal, causing the relay to drop out, and permit the plunger of the flow reversing valve to drop to its normal operating position.

The entire system is a fully automatic one, requiring no attention on the part of any operator. Any conditions developing in the press will accordingly receive prompt response by the system, to compensate for such conditions and relieve the same, to restore the press to normal operation.

The system may, if desired, be made responsive to manual control on the part of an operator, and the change is readily made, by eliminating the solenoid control on the flow reversing valve and incorporating in the valve structure, a handle on the plunger stem 133, for operation by an operator, as and when desired.

It will be apparent from the above description of my invention that the same is capable of modification and alteration, without departing from the spirit of the invention, and I accordingly do not desire to be limited in my protection to the specific details disclosed, except as may be necessitated by the prior art and the appended claims.

I claim:

1. An extrusion press comprising a compression chamber; means for compressing material in said chamber, said chamber having an opening therein through which to discharge material therefrom; and means for automatically maintaining a substantially constant pressure in said chamber in spite of pressure changing conditions developing therein, said last means including an adjustable closure for said discharge opening, capable of opening in response to pressure increasing conditions developing in said chamber, a hydraulic system for controlling movement of said closure and including a cylinder and piston operatively associated with said closure, a source of liquid for said system, a feed line leading to said cylinder, a return line from said cylinder, a pump in said system for developing pressure of liquid in said feed line, and a pressure sensitive shunt interconnecting said feed line and said return line to cause a slight reversal in the flow of liquid sufficient to maintain the pressure substantially constant.

2. In combination, an extrusion press having a pressure chamber with a discharge passage therefrom, a closure in said discharge passage adapted for operation to alter the capacity of said discharge passage to handle the discharge from said pressure chamber, a compression member in said pressure chamber, a motor in

driving connection with said compression member, a hydraulic system for applying pressure to said closure in the direction of closing the same, a reversing valve in said system adapted upon actuation, to reverse the pressure on said closure, and means responsive to an overload on said motor for reversing said valve to force said closure to a wide open position.

3. An extrusion press comprising a compression chamber having an open end, a compression element in said chamber adapted to compress material fed therein and discharge the same through said open end, a shaft extending through said open end and carrying a piston, a closure slidably mounted on said shaft for operation into and out of said open end to adjust the discharge therethrough, said closure having a chamber connected thereto and slidably enclosing said piston to create a piston chamber on either side of said piston, means for developing hydraulic pressure in one of said piston chambers urging movement of said closure toward said open end of said compression chamber, a reversing valve for shifting said hydraulic pressure to the other of said piston chambers and automatic means for actuating said valve upon the occurrence of an overload in said compression chamber.

4. An extrusion press comprising a compression chamber having an open end, a compression element in said chamber adapted to compress material fed therein and discharge the same

through said open end, a shaft extending through said open end and carrying a piston, a closure slidably mounted on said shaft for operation into and out of said open end to adjust the discharge therethrough, said closure having a chamber connected thereto and slidably enclosing said piston to create a piston chamber on either side of said piston, means for developing hydraulic pressure in one of said piston chambers urging movement of said closure toward said open end of said pressure chamber, a relief valve included in said hydraulic pressure developing means, permitting movement of said closure away from said open end in response to pressure increasing conditions within said pressure chamber, while maintaining substantially constant hydraulic pressure against said closure.

5. An extrusion press comprising a compression chamber having an open end, a compression element in said chamber adapted to compress material fed therein and discharge the same through said open end, an adjustable closure at said open end for altering the discharge opening at said end, means normally urging said closure against the pressure of said discharge, and means for effecting a full and quick opening of said closure in response to an overload pressure in said chamber.

EDGAR T. MEAKIN.
